UNITED STATES PATENT OFFICE.

JOHN M. CARRÈRE, OF NEW YORK, N. Y.

PORTFOLIO.

SPECIFICATION forming part of Letters Patent No. 429,166, dated June 3, 1890.

Application filed February 18, 1890. Serial No. 340,940. (No model.)

To all whom it may concern:

Be it known that I, JOHN M. CARRÈRE, a resident of the city, county, and State of New York, have invented an Improvement in Portfolios, of which the following is a specification.

The object of my invention is to provide an improved portfolio of simple construction; and it consists, essentially, in a novel method of stringing a portfolio, which will be more fully set forth in the subsequent part of the specification, reference being had to the accompanying drawings, forming a part of the same, wherein—

15 Figure 1 represents a perspective view of my portfolio; Fig. 2, a side view of the same; Fig. 3, a view in cross-section of my portfolio closed on the lines *c c*, Fig. 2; Fig. 4, a view in cross-section of my portfolio open on the lines 20 *c c*, Fig. 2; Fig. 5, a perspective view of my portfolio, showing the covers held open, one being held at an angle to the other and resting on the same by means of the string.

25 My portfolio may be made of any material now used in portfolios, and consists of two pieces of the same size hinged and held together by a string or tape.

The letter *A* in the drawings represents one cover, and *B* the other.

30 I will now describe my method of stringing. The string or tape *D* is passed through a hole *a* in the upper part of the cover *A*, from the outside of the said cover *A*, and, passing along the inside of *A*, passes through the hole *b*, situated, preferably, in the center of *A*; then on the outside of *A* to the hole *d* on the one side of *A*, through *d* to the hole *e* on the same side of the cover *B*, through *e* and along the outer surface of *B* to the hole *f* on the opposite side of *B*, through *f* to the hole *g*, aligned therewith in the cover *A*; then along the outside of *A* to the hole *b*, through *b* and down on the inside of *A* to the hole *h* at the lower side of *A*, through *h* and around the end of the covers to the hole *i* on the lower side of the cover *B*, through *i*, thus forming a hinge *x*; then along the inside of the cover *B* to the hole *j* at the upper side of *B*, and through *j*, thus completing the operation. A knot or other 45 stop is now placed on the ends of the tape or

string to prevent the same from slipping through the holes *a* and *j*. By pulling these ends the strings are drawn taut and the portfolio-covers closed. To hold the portfolio closed these ends may be tied or fastened together in any convenient manner, as at *p*, Figs. 2 and 3.

It is evident that in my improved construction if the covers of the portfolio are allowed to rest on the strings, the said strings will 60 bind in the holes, thus holding the covers open at any convenient angle. One particular advantage of my portfolio is very well illustrated in Fig. 5, in which the covers are held at a large angle, the cover *B* resting on 65 the cover *A* and held by the braces *y y*, that are formed by the string between the holes *d e* and *g f*. This affords an easy means, if so desired, of reading a catalogue of the drawings or photographs contained in the portfolio, 70 if said catalogue is printed or placed on the inside of the cover *B*. The contents of the catalogue are by this method exposed to view.

This form of portfolio is particularly advantageous in holding architects' drawings, 75 and its principal advantages are its simple construction, its easy method of operation, and the method of holding one cover at an angle to the other that a list printed on one can be read.

80 Therefore, having described my invention, what I claim is—

1. The covers *A B*, combined with the single continuous cord *D*, which is laced through said covers at one end to form a hinge *x*, 85 which is also laced through said covers at the opposite end to form a tie *p*, substantially as herein shown and described.

2. The covers *A B*, combined with the cord *D*, which is laced through said covers to form 90 the hinge *x*, and the braces *y y* between the holes *d g* of the cover *A* and the holes *e f* of the cover *B*, substantially as herein shown and described.

3. The covers *A B*, combined with the cord 95 *D*, which is laced through said covers to form the hinge *x*, the braces *y y* between the holes *d g* of the cover *A* and the holes *e f* of the cover *B*, and the tie *g*, substantially as herein shown and described.

4. In a portfolio, the combination of the
cover A with the cover B and with the string
D, which is passed through a hole in the up-
per part of the cover A, then through a hole
5 in the center of said cover, then through a
hole on one side of the said cover, then through
a hole on one side of the opposite cover B,
then through a hole on the opposite side of
same cover, then back again to a hole on the
10 side of the cover A, then through the center

hole of the cover A and down to a hole at the
lower side of the cover A and around both
covers, forming a hinge, to a hole in the lower
side of the cover B, and then through a hole
near the top of the said cover B, as and for 15
the purposes specified.

JOHN M. CARRÈRE.
